FOLDING TABLE

William P. De Saussure, Jr., Englewood, N. J., assignor to De Saussure Equipment Company, West New York, N. J., a corporation of Delaware

Application December 24, 1934, Serial No. 758,897

6 Claims. (Cl. 311—85)

This invention relates to tables having folding legs. The invention aims to provide an improved folding leg table of the type which has the legs connected in pairs which are pivotally mounted to fold inward to lie parallel with the table top and are connected by means whereby when either pair of legs is folded or unfolded the other pair will be similarly moved; and to provide a folding table which shall be strong and rigid when the legs are extended even though the top be made of light thin material such as thin ply board.

To these ends, the two pairs of legs of a table according to the invention are mounted between two parallel spaced side bars beneath the table top, one pair of legs being fixedly pivoted to the side bars and the other pair of legs having their ends pivotally and slidably connected to the side bars and being pivotally connected at points spaced from but near their upper ends to links which are fixedly pivoted to the side bars, and connecting rods extending parallel to the side bars are pivotally connected at one end to the sliding ends of the second pair of legs and at their other ends to the sliding ends of links which are connected at one end to the first pair of legs at points spaced from but near their upper ends and at the other end are pivotally and slidably connected to the side bars. By this arrangement, when either pair of legs is moved from its folded to its unfolded position or from its unfolded to its folded position, the other pair of legs will be similarly moved, the movement being transmitted by endwise movement of the connecting rods. Most desirably, and in accordance with the invention, the side bars are connected to form a rigid frame, so that the side bars and the legs and the operating connections form a unit apart from the table top, the frame providing a support for the table top to which it may be secured in any suitable manner.

A full understanding of the invention can best be given by a detailed description of a table embodying all the features of the invention in the form now considered best and such description will now be given in connection with the accompanying drawings showing such a table. In said drawings:—

Fig. 1 is a bottom plan view of the table with the legs in folded position;

Fig. 2 is a section on the line 2—2 of Fig. 1, with the legs unfolded;

Fig. 3 is a side elevation of the table with the legs in folded position;

Fig. 4 is a side elevation of the table with the legs in unfolded or extended position;

Fig. 5 is a section on the line 5—5 of Fig. 1 with the legs extended;

Fig. 6 is a section on the line 6—6 of Fig. 1 with the legs extended;

Figs. 7 to 11, inclusive, are detail views showing the operation of the means for locking the legs in extended position; and

Fig. 12 is a perspective view of one of the catches which hold the legs in extended position.

The table shown comprises a wooden top 10, a rectangular metallic frame 11 on which the top rests and to which it may be secured in any suitable manner, as by means of rivets, and two pairs of folding legs 12 and 13. The frame comprises two spaced parallel side bars 14 and 15 formed of angle bars set with one flange horizontal and the other flange depending vertically, two end members 16 and 17 rigidly connected to the side bars and which may also be formed of angle bars, and an intermediate cross bar 18 extending between the side bars. The end bars and the intermediate bar are desirably connected to the side bars by spot welded angle pieces 19. The legs are most desirably formed of rectangular metal tubing, and the two legs of each pair are connected by a cross bar 20 which may also be of rectangular tubing and which is secured to the legs by spot welded plates 21. A handle 22 is provided for convenience in carrying the table when folded.

The legs of one pair, as the legs 12, are pivotally connected to the vertical flanges of the side bars to swing about fixed points 25. The other pair of legs, 13, are pivotally and slidably connected to the vertical flanges of the side bars by pivots 26 extending through longitudinal slots 27 in said flanges, and at points spaced from but near their upper ends these legs are connected by pivots 28 to links 29, the other ends of which are pivotally connected to the vertical flanges of the side bars at fixed points 30. This pair of legs will, therefore, in being moved between its folded and unfolded position, swing about the pivots 28 on the links 29, and as the legs change their angular position their pivot pins 26 will slide in the slots 27 and the links will swing between the position shown in Figs. 2 and 4 and a position in which they lie substantially parallel with the side bars and the folded legs.

Two connecting rods 35, one extending outside of and generally parallel to the vertical flange of each of the side bars 14 and 15, are connected each at one end to one of the sliding pivots 26. At its other end each of the connecting rods 35 is pivotally connected by a pivot pin 36 extending through a longitudinal slot 37 in the vertical flange of the adjacent side bar to a link 38, the other end of which link is pivotally connected to one of the legs 12 at a point 39 spaced from the pivot 25 a distance equal to the distance between the pivots 26 and 28 of the legs 13.

The two pairs of legs are thus pivotally mounted.

ed and connected through the connecting rods 35 and links 38 whereby if either pair is moved angularly between its folded and unfolded position the other pair will be given a similar movement in the opposite direction, so that if either pair of legs is moved from its folded to its unfolded, or extended, position the other pair will be simultaneously extended, and if either pair is moved from its extended to its folded position the other pair will simultaneously be moved to its folded position.

As the connecting rods are guided at each end by the pins 26 and 36 sliding in the aligned slots 27 and 31 and move only endwise, they are not subjected to any bending strain and may consequently be of comparatively light weight even when the table is of such length as to require comparatively long connecting rods and is of comparatively heavy construction. The connecting rods are most desirably made of flat strips of steel or other suitable material lying close against the outside of the downwardly extending flanges of the side bars. The rods are thus prevented by the flanges from buckling inwardly. To prevent them from buckling outwardly, if made sufficiently light so that there might be danger of their buckling under the thrust thereon, guide pieces 40 may be provided formed by short angle pieces spot-welded or otherwise secured to the upper flange of the side bars.

The upper or table ends of the legs are offset outwardly so that the legs when folded are spaced from the side bars to provide space therebetween for the links 29 and 38 which are pivotally connected to the outer sides of the legs and to the inner sides of the vertical flanges of the side bars. The links are most desirably formed of flat strips of steel or other suitable material, and the links 38 which transmit the moving force between the legs 12 and the connecting rods 35 most desirably have spot-welded thereto at their inner ends a short metal strip 41 obliquely bent into U-shape to provide the link with a forked end which embraces the vertical flange of the side bar and the end of the connecting rod 35. There is thus provided spaced bearings for the pivot 36 between which the pivot is engaged by the rod 35.

In order that, when the legs 12 are swung outward from their folded position, the pull of the connecting rods 35 on the pivots 26 shall be effective at the beginning of the outward movement of the legs 12 to start the outward swing of the legs 13, the pivots 28 are, as shown, placed nearer to the outer edge of the legs 13 than the pivots 29 and nearer to the outer edge of the links 38 than the pivots 30 so that when the legs are in folded position the pivots 28 will lie below a plane passing through the pivots 26 in the direction of pull of the rods 35. Similarly, in order that, when the legs 13 are pulled outward from their folded position, the thrust of the connecting rods on the pivot 36 shall be effective to start the outward swing of the legs 12, the pivots 39 are placed nearer to the outer edge of the legs 12 than the pivots 25 and nearer to the outer edge of the links 38 than the pivots 36, so that when the legs are in folded position the pivots 39 will lie below a plane passing through the pivots 25 in the direction of the thrust of the rods 35. With the pivots so arranged, it is unnecessary to pull on both pairs of legs to start them from their folding position, pulling on one pair serving to start and thereafter complete the unfolding movement of the other pair.

The legs are locked in unfolded or extended

position by means co-operating with the connecting rods 35 to hold the rods against longitudinal movement. For this purpose a rocking locking bar 45 is provided extending transversely across the table with its ends journalled in and extending through openings in the vertical flanges of the side bars 14 and 15 in position to bear against the upper edge of the connecting rods and to hold the rods flexed slightly downward between the pivots 26 and 36 by which they are supported. The upper edge of each rod is cut out to provide a shoulder 46 against which the end of the bar 45 engages when the legs are in extended position and the connecting rods have been moved to the position shown in Figs. 4 and 10. When the connecting rods are moved to this position they spring upward so that the shoulders 41 are engaged by the ends of the bar. The locking bar is provided with an operating piece or wing 47 whereby the bar may be rocked, and the ends of the bar are formed each with a flattened cam face 48 so that when the bar is rocked from the position shown in Figs. 4 and 10 to that shown in Fig. 11 the edge of the cam face which is away from the shoulder 46 acts to depress the connecting rod and at the same time the edge of the cam face in engagement with the shoulder is raised so that if the table legs are then swung inward from their extended position and the connecting rods thereby moved to the right from the position shown in Figs. 4, 10 and 11, the cam faces of the locking bar will ride over the shoulder further depressing the connecting rods to permit the connecting rods to move to the right.

The connecting rods are desirably provided each with a shallow notch 49 for receiving the end of the locking bar when the connecting rods are in folded leg position. These notches are formed with inclined sides so as not to prevent endwise movement of the connecting rods when it is desired to unfold the table legs, but they serve normally to hold the legs in folded position, the resistance to endwise movement resulting from entrance of the ends of the locking bar into these notches being sufficient to serve this purpose.

If the upper edge of that portion of the connecting rods against which the ends of the locking bar bear were made to extend parallel to the direction of movement of the rods, the deflection of the rods under the pressure of the ends of the locking bar would increase as the points of engagement of the ends of the locking bar were shifted in the direction from the middle of the rods toward either end of the rods, that is, in the arrangement shown, as the rods moved to the right or toward the position shown in Figs. 3 and 7. To avoid this, the upper edge of the connecting rods against which the ends of the locking bar bear between the shoulder 46 and the notch 49 is made to slope slightly downward in the direction from the shoulder 46 toward the end of the bar. This slight slope of the bearing edge of the rods is conveniently provided by forming the connecting rods from strips having parallel straight edges and bending the rods slightly upward between their supported ends as shown.

It is to be understood that while the invention is especially adapted for embodiment in a table of such length that the legs when folded do not overlap, yet the invention clearly is not limited in its application to such tables; also, that the invention is not to be otherwise limited to the exact construction and arrangement of parts shown and to which the foregoing description has

been largely confined, but that it includes changes and modifications thereof within the claims.

What is claimed is:

1. A folding leg table, comprising two parallel spaced side members projecting downwardly beneath the table top, a pair of legs pivotally connected to said side members near one end of the table, another pair of legs pivotally and slidably connected to the side bars near the other end of the table, links pivotally connected to the first pair of legs at points spaced from but near their upper ends and pivotally and slidably connected to the side members, links pivotally connected to the second pair of legs at points spaced from but near their upper ends and pivotally connected to the side members, and connecting rods extending parallel to the side members and pivotally connected at one end to the slidable end of the links of the first pair of legs and at the other end to the slidable end of the second pair of legs, and means for releasably locking the legs in unfolded position comprising a rocking bar extending transversely of the connecting rods and having its ends journaled in openings in the side members positioned to cause the bar to bear against and slightly flex the connecting rods, the connecting rods having shoulders positioned to be engaged by the rocking bar when the legs are in unfolded position and the rod-engaging portions of the locking bar being shaped to provide cam faces whereby when the bar is rocked one edge of each cam face will force the connecting rod away from the rocking bar and the other edge of the cam face will rise clear of the shoulder, and means for rocking the bar. 25
2. A folding leg table, comprising two parallel spaced side members projecting downwardly beneath the table top, a pair of legs pivotally connected to said side members near one end of the table, another pair of legs pivotally and slidably connected to the side bars near the other end of the table, links pivotally connected to the first pair of legs at points spaced from but near their upper ends and pivotally and slidably connected to the side members, connecting rods extending parallel to the side members and pivotally connected at one end to the slidable end of the links of the first pair of legs and at the other end to the slidable end of the second pair of legs, and a latch co-operating with one of said connecting rods for releasably holding the legs in unfolded position. 30
3. A folding leg table, comprising two parallel spaced side members projecting downwardly beneath the table top, a pair of legs pivotally connected to said side members near one end of the table, another pair of legs pivotally and slidably connected to the side bars near the other end of the table, links pivotally connected to the first pair of legs at points spaced from but near their upper ends and pivotally and slidably connected to the side members, links pivotally connected to the second pair of legs at points spaced from but near their upper ends and pivotally connected to the side members, connecting rods extending parallel to the side members and pivotally connected at one end to the slidable end of the links of the first pair of legs and at the other end to the slidable end of the second pair of legs, the frame and legs and operating connections forming a complete unit apart from the table top and the table top resting on and being secured to the frame. 40
6. A folding leg table, comprising a table top, a rectangular metal frame composed of end members and parallel side members formed by angle bars arranged with one flange horizontal and the other flange extending vertically downward therefrom, a pair of legs pivotally connected to the vertical flanges of the side members, another pair of legs pivotally and slidably connected to the vertical flanges of the side members by pivot pins extending through longitudinal slots in said flanges, links pivotally connected to the first pair of legs at points spaced from but near their upper ends and pivotally and slidably connected to said flanges by pins extending through longitudinal slots in the flanges, links pivotally connected to the second pair of legs at points spaced from but near their upper ends and pivotally connected to said flanges, and connecting rods extending parallel to and outside of said flanges and connected at one end to the pivot extending from the slidable end of the links of the first pair of legs and at the other end to the pivot extending from the slidable end of the second pair of legs. 55
7. A folding leg table, comprising two parallel spaced side members projecting downwardly beneath the table top, a pair of legs pivotally connected to said side members near one end of the table, another pair of legs pivotally and slidably connected to the side bars near the other end of the table, links pivotally connected to the first pair of legs at points spaced from but near their upper ends and pivotally connected to the side members, connecting rods extending parallel to the side members and pivotally connected at one end to the slidable end of the links of the first pair of legs and at the other end to the slidable end of the second pair of legs, and means for releasably locking the legs in unfolded position comprising a rocking bar extending transversely of the connecting rods and having its ends journaled in openings in the side members positioned to cause the bar to bear against and slightly flex the connecting rods, the connecting rods having shoulders positioned to be engaged by the rocking bar when the legs are in unfolded position and the rod-engaging portions of the locking bar being shaped to provide cam faces whereby when the bar is rocked one edge of each cam face will force the connecting rod away from the rocking bar and the other edge of the cam face will rise clear of the shoulder, and means for rocking the bar. 70
